UNITED STATES PATENT OFFICE

164,438

GIRDLE

Milton Mayer, New York, N. Y., assignor to Vanity Corset Company, Inc., New York, N. Y., a corporation of New York

Application May 21, 1951, Serial No. 15,267

Term of patent 14 years

(Cl. D20—2)

To all whom it may concern:

Be it known that I, Milton Mayer, a citizen of the United States, residing in the city, county, and State of New York, have invented a new, original, and ornamental Design for Girdles, of which the following is a specification, reference being had to the accompanying drawing, forming part thereof, in which:

Fig. 1 is a front elevational view of a girdle, showing my new design;

Fig. 2 is a rear elevational view of the same; and

Fig. 3 is a side elevational view of the same.

I claim:

The ornamental design for a girdle, substantially as shown.

MILTON MAYER.
